UNITED STATES PATENT OFFICE.

DAVID B. SALTSMAN, OF DOWAGIAC, MICHIGAN, ASSIGNOR TO DOWAGIAC MANUFACTURING COMPANY, OF DOWAGIAC, MICHIGAN.

GRAIN-DRILL.

SPECIFICATION forming part of Letters Patent No. 737,153, dated August 25, 1903.

Application filed April 16, 1903. Serial No. 152,922. (No model.)

To all whom it may concern:

Be it known that I, DAVID B. SALTSMAN, a citizen of the United States, residing at the city of Dowagiac, in the county of Cass and State of Michigan, have invented certain new and useful Improvements in Grain-Drills, of which the following is a specification.

This invention relates to improvements in grain-drills.

10 It relates particularly to improvements in disk furrow-openers for grain-drills, although it is adapted for use in other relations.

The objects of this invention are to provide an improved disk furrow-opener for grain-drills and the like which is compact, strong and durable, and simple in its construction.

15 A further object is to provide an improved bearing for disk structures of the class described whereby the strain upon the disk in use is reduced to a minimum.

Further objects and objects relating to structural details will definitely appear in the detailed description to follow.

I accomplish the objects of my invention 25 by the devices and means described in the following specification.

The invention is pointed out in the claims.

A structure embodying the features of my invention is illustrated in the accompanying 30 drawings, forming a part of this specification, in which—

Figure 1 is a detail side elevation view of a structure embodying the features of my invention. Fig. 2 is an enlarged detail side elevation view of a portion of the boot, showing its structure for the attachment of the disk-bearing. Fig. 3 is an enlarged detail view taken on a line corresponding to line 3 3 of Figs. 1 and 2. Fig. 4 is an enlarged detail 40 sectional view of a modified structure corresponding to the view shown in Fig. 3.

In the drawings the sectional views are taken looking in the direction of the little arrows at the ends of the section-lines, and 45 similar letters of reference refer to similar parts throughout the several views.

Referring to the lettered parts of the drawings, the boot A is of the usual or any convenient form and construction and is provided with a forwardly-projecting bracket to 50 which the draw-bar A' is attached. Toward

the lower end of the boot is a projection A', which is adapted to receive the bearing-blocks C. The bearing-blocks are secured in position on the boot by screw-bolts E. If desired, 55 one bolt may be used for this purpose. Each bearing-block C is provided with an annular flange or disk-like head c. A bearing-plate B', having an outwardly-projecting flange b, adapted to embrace the head c of the bearing-block B, is mounted thereon. The bearing-plate is also provided with a shoulder b', adapted to receive the disk B, which is secured to the plate by rivets or in any other suitable manner. Secured to the outer face 65 of each disk over the bearing-blocks C is a cap B''. The cap B'' is preferably detachably secured in position by a set-screw or bolt, which is passed through the disk and into the bearing-plate B', thereby clamping the disks 70 and forming a very rigid support therefor. The cap B'' holds the bearing-plate in position against the bearing-block and in conjunction therewith forms the bearing for the disk. Oil is supplied to the bearing in any 75 convenient or usual manner, the means not being here illustrated.

In the modified construction shown in Fig. 4 the bearing-plate B' is secured to the outer instead of the inner face of the disk. The 80 parts are substantially the same as those in the preferred construction, though it lacks the advantages of clamping the disk between the bearing-plates B' and the bearing-cap, and the structure has the further disadvantage 85 of not being quite so compact. It is, however, a very desirable structure.

With the parts thus arranged the disks are supported in such a manner that the strain thereon is reduced to a minimum. 90

The structure is very economical to produce, as the parts are simple and readily assembled. If desired, the structure may be readily disassembled by removing the cap B'' and the retaining-bolt E for the bearing-block, 95 and the parts are completely disassembled.

I have illustrated and described my invention applied to double-disk structures adapted for use as furrow-openers for grain-drills. It is evident, however, that the same is applicable for use in other relations. I have illustrated and described the same in the form 100

preferred by me on account of its economy of production and durability in use. I am aware, however, that it is capable of very considerable variation in structural details 5 without departing from my invention.

Having thus described my invention, what I claim as new, and desire to secure by Letters Patent, is—

1. The combination of a boot; bearing-blocks C having annular flanges c thereon secured thereto; bearing-plates B' having shoulders b and outwardly-projecting flanges b' thereon, mounted on said bearing-blocks; bearing-caps B'', adapted to fit over said flanges b', secured to said bearing-plates; and disks B adapted to fit said shoulders clamped between said plate and cap, as specified.
2. The combination of a boot; bearing-blocks C having annular flanges c thereon secured thereto; bearing-blocks B' having outwardly-projecting flanges b' thereon, mounted on said bearing-blocks; bearing-caps B'' adapted to fit over said flanges b', secured to said bearing-plates; and disks B clamped between said plate and cap, as specified.
3. The combination of a boot; a bearing-

block C having an annular flange c thereon secured thereto; a bearing-block B' having an outwardly-projecting flange b' thereon, mounted on said bearing-block; a bearing-cap B'' adapted to fit over said flanges b', secured to said bearing-plate; and disks B clamped between said plate and cap, as specified.

4. The combination of a boot; a bearing-block, having a disk-like head at its outer end, secured thereto; a bearing-plate having an outwardly-projecting flange adapted to embrace said head, mounted on said block; a bearing-cap secured to said plate; and a disk 35 40 clamped between said bearing plate and cap.

5. The combination of a bearing-block having a head at its outer end; a bearing-plate mounted thereon; a bearing-cap adapted to embrace said head, secured to said bearing-plate, and a disk 45 secured to said plate.

In witness whereof I have hereunto set my hand and seal in the presence of two witnesses.

DAVID B. SALTSMAN. [L. S.]
